TELEPHONE SYSTEM

Esmond Philip Goodwin Wright, London, England, assignor to Western Electric Company, Incorporated, New York, N. Y., a corporation of New York

Application August 21, 1936, Serial No. 97,113
In Great Britain October 4, 1935

21 Claims. (Cl. 179—18)

This invention relates to telephone systems and particularly to systems comprising automatic switching equipment for use in completing connections.

3 The object of the invention is to facilitate the establishment of desired connections and to otherwise increase the efficiency and adaptability of automatic switching equipment in telephone systems.

10 A feature of the invention is a telephone system in which a special switch is provided for use in place of the usual switching equipment for directly connecting one of certain subscribers' lines with another of these lines. The switch is selectively controlled by non-locking keys at the stations, a key being provided at each station for each of the other lines to which the switch gives direct access.

20 Another feature of the invention is a telephone system in which the special switch, which is operatively controlled by a non-locking key at a subscriber's station to directly connect this station with a certain other station, is released by replacing the receivers at these stations.

25 Another feature of the invention is a telephone system in which a special switch is provided for directly interconnecting any two of certain stations, the switch being arranged to give the calling station a busy signal if the station with which connection is desired is busy, the busy signal being terminated and the desired connection established if the called station becomes idle before the calling station releases the switch.

30 These and other features of the invention will be more completely described by considering a telephone system in which the invention is embodied, one such system being illustrated in the drawing which forms a part of this specification. The invention is not limited in its application to the particular system shown but is, in general applicable to any manual, automatic or semi-automatic system.

40 Referring to the drawing, a telephone system is represented schematically by two subscribers' stations A and B, a finder switch LF and a start circuit SC.

45 The special finder switch LF comprises an operating magnet LFM, a set of eight brushes and an associated bank of terminals. The brushes LFM₁, LFM₂, LFM₃, LFM₄ and LFM₈ are used for establishing and controlling the establishment of connections with calling stations such as B; the brushes LFM₅, LFM₆ and LFM₇ are used for establishing connection with a called station such as A. More than one of the special finder

switches LF may be provided, the start circuit SC being arranged as shown in the drawing to control a group of four of such switches controlled from one or more stations B and having access to one or more stations A. When associated with 5 a group of four such finder switches, the start relay ST is provided with three more contacts similar to st₃ and three more contacts similar to st₄.

The station A represents one to which calls 10 from one or more other stations may be completed by a special finder switch LF controlled from the calling station. The station B represents one which is provided with special non-locking keys K₁, K₂ for use in controlling the operation of a special finder switch LF to establish connection with a desired station to which the switch LF has direct access. A special line relay Q is provided for the station B shown and a similar relay is provided for each other station which is 20 arranged to control a finder switch LF. Of course, the usual line relay and other line circuit apparatus is provided for the line of each of these stations but is not shown in the drawing other than being represented by the dotted lines leading 25 to the terminals and associated set of brushes of line finder and final selector switches, which switches are adapted to complete regular calls to and from these lines. If the central office equipment is manually operated, the lines are connected to jacks at an operator's position instead of being connected to the banks of line finder and selector switches, as shown.

30 The upper springs of keys K₁, K₂ at a station B are connected to the exchange by a common conductor, and in the exchange to the special line relay Q; so that operation of any one of the keys causes the operation of relay Q to start one of the finders LF. The middle springs of keys K₁, K₂ are connected to the exchange by individual 40 conductors, and in the exchange to adjacent terminals in the group accessible to brush LFM₁. The lower springs of keys K₁, K₂ are connected to the exchange by a common conductor and in the exchange to relay DA of the start 45 circuit SC.

45 The line from each station such as B is connected to as many positions in the finder switch LF as there are stations such as A to which this switch gives direct access; and in each of these positions, 50 a connection is established from the station such as B to a different one of the stations such as A. Thus the line of station, such as B, is connected to four succeeding terminals in the terminal groups to which brushes LFM₃ and LFM₄ have 55

access, and the line of each station such as A is connected to a different one of the corresponding four terminals in the terminal groups to which brushes LFM5 and LFM6 have access. The line 5 A is also connected to one of the terminals in each such group of four succeeding terminals to which brushes LFM5 and LFM6 have access so that each of the stations such as B will have direct access to the line A. If station A is also one 10 provided with a set of keys K1, K2, and served by the same finder or finders as is station B, then the line of station A is connected to a group of four succeeding terminals in the terminal groups to which brushes LFM3 and LFM4 have access. 15 And if line B is also one to which the switch LF has access on calls from stations provided with the keys K1, K2, then this line is connected to one terminal of each group of four succeeding terminals to which brushes LFM5 and LFM6 have access. 20

Assuming now that the subscriber at station B desires a quick and direct connection with station A, key K1 is actuated thereby momentarily closing a circuit from battery in the start circuit 25 SC, through the winding of relay DA, both contacts of key K1, back contact of spring q2 and winding of relay Q to ground. The special line relay Q is operated by the current in this circuit but relay DA does not operate. The rectifier MRA is poled to prevent the operation of 30 relay Q in series with the cut-off relay (not shown) to which it is normally connected at the back contact of spring q4. Relay Q locks through the front contact of spring q2 and the 35 back contact s21 of relay SZ in the start circuit. At contact q4, relay Q connects ground over the test conductor to operate the cut-off relay (not shown) of the regular line circuit to prevent seizure of the line on an incoming call; and, at 40 contact q1, relay Q closes a circuit for operating start relay ST. The rectifier MRA prevents the short-circuiting of the winding of relay Q when spring q4 closes its front contact.

At its contact st4, relay ST closes a circuit 45 which includes contacts k1 and ka1 for operating the driving magnet LFM; at the other like contacts (not shown) of relay ST, similar circuits are closed for operating the driving magnets of other idle finders in the group. The 50 brushes of switch LF are thereby advanced step-by-step until brush LFM1 finds the terminal to which key K1 is connected at which time a circuit is closed from ground through contact st3, both windings of relay K in series, brush LFM1, 55 terminal to which key K1 is connected and through the lower contact of key K1 and winding of DA of the start circuit to battery. Relay DA is not operated but relay K is operated by the current in this circuit. At the back contact of 60 spring k1, the circuit for operating the magnet LFM is opened to prevent further advance of the brushes; and, at the front contact of spring k1, the left winding of relay K is short-circuited by the ground at contact st4, thereby increasing the 65 drop in potential through the right winding of relay K sufficiently to prevent seizure of the line by any of the other special finder switches which may be hunting. At contact k2, relay K closes a circuit for operating relay KA, and relay 70 KA locks through its contact ka2, brush LFM2, and contact q3, to ground. The key K1 having been actuated long enough for the switch LF to find the position corresponding to the calling and called stations, the calling subscriber leases key K1 and removes the receiver from the 75

receiver hook and a circuit is closed from battery through the lower winding of relay S, contact ka3, brush LFM3, over conductor a and through the calling station B, back over conductor b, through brush LFM4, contact ka4, and through the upper winding of relay S to ground. Relay S operates and at its contact s4 connects ground through brush LFM8 and rectifier MRA to short-circuit the winding and thus cause the release of relay Q. The release of relay Q causes 10 the release of relay ST, thereby stopping the operation of any other line finder which was set in operation by relays Q and ST. The release of relay ST also causes the release of relay K. Relay KA remains operated under the control of 15 contact s1 of relay S.

If station A is idle when the brushes of switch LF are advanced to one of the positions in which this line is accessible, the test relay T is operated by the current in a circuit from ground through 20 the winding of relay T, contact s8, brush LFM1, to battery through the cut-off relay (not shown) of the line to station A. Relay T closes a circuit at its contact t1 for operating relay TT. Relay TT locks through its contact tt1 and contact s1; 25 and at its contact tt5 short-circuits and causes the release of relay T. The operation of relay TT closes a ringing circuit from the ringing source, through the left winding of relay F, back contact of spring f3, contact tt4, brush LFM6, 30 over the line to station A and through the ringer (not shown) thereat, back through brush LFM5, contact tt3, and back contact of spring f2 to grounded battery. Relay F is marginal and does not operate until the receiver is removed at station A. Ringing tone lead RTL is connected through the front contact of spring tt2 and contact f1, in parallel with the lower winding of 35 relay S, to conductor a of the line to station B. When the receiver is removed at station A and 40 relay F operates, contact f4 opens the short circuit around the right winding of relay F so that relay F holds under control of contact tt6, the ringing circuit is opened at the back contacts of springs f2 and f3; and a talking circuit is 45 closed through the windings of inductance I, the front contacts of springs f2 and f3 and through brushes LFM5 and LFM6 and over the line and through the telephone at station A. Talking battery is supplied to station B through 50 the windings of relay S.

If the called station is busy, the test terminal with which brush LFM1 is engaged is at ground potential and relay T does not operate. In this case the busy-tone conductor BTL is connected 55 through contact s2, back contact of spring tt2 and contact f1, to the a conductor of the line to station B in parallel with the lower winding of relay S. If, before the subscriber at station B releases the connection, the called station becomes idle, relays T and TT are energized and the ringing circuit is closed as hereinbefore described.

If the calling subscriber does not hold the key K1 operated long enough for the line relay Q to 65 close its locking circuit, removal of the receiver will initiate a regular connection. If the key is depressed long enough to operate and lock relay Q but the subscriber does not thereafter remove the receiver, a finder LF finds the marked position as hereinbefore described but relay S does not operate. In this case, relay Q remains operated until its circuit is opened a predetermined interval of time after the start relay ST is operated. To this end, relay ST connects ground 70 to the 75

from contact s_22 , through its contact s_22 to conductor STL to start the operation of a common timing circuit if not already in operation. Relay ST also connects the winding of relay SA, through contact s_11 , the back contact of spring sa_2 and contact s_23 to the pick-up lead SL of the timing circuit, to which lead ground is connected at the beginning of each such predetermined interval measured off by the timing circuit. Relay SA is operated, as soon after it is connected to lead SL as this lead is connected to ground, and locks through the front contact of spring sa_2 . At contact s_11 , relay SA connects the winding of relay SZ to lead ZL, to which conductor ground is connected at the end of the desired interval as measured by the timing circuit. Relay SZ operates and, at its contact s_21 , opens the holding circuit of relay Q. Relays Q, ST, SA and SZ are thereupon released in the order named.

If the subscriber at station B desires simultaneous connection with more than one of the stations to which the special line finders give access, depression of each key corresponding to a desired station causes the operation of one of the finders and connection is then established with the desired stations.

The special finder LF might be used for completing incoming calls from another exchange by providing a group of relays, or other switch, operated over the interoffice trunk for controlling the special finders as desired.

What is claimed is:

1. In a telephone system comprising subscribers' lines, normally-employed switching means for establishing connections between any two of said lines, and a switch for establishing direct connections between any one of certain of said lines when calling and any desired one of certain of said lines, said switch operating only as a finder switch.

2. In a telephone system comprising subscribers' lines, normally-employed switching means for establishing connections between any two of said lines, and a switch for establishing direct connections between any one of certain of said lines when calling and a particular one of said lines, said switch operating only as a finder switch.

3. In a telephone system comprising subscribers' lines, normally-employed switching means for establishing connections between any two of said lines, and a switch for establishing direct connections between any one of certain of said lines and any of other certain ones of said lines, said switch operating only as a finder switch.

4. In a telephone system comprising subscribers' lines, normally-employed switching means for establishing connections between any two of said lines, and a switch for establishing direct connections between any two of certain of said lines, said switch operating only as a finder switch.

5. In a telephone system comprising subscribers' lines, normally-employed switching means for establishing connections between any two of said lines, a switch for establishing direct connections between any one of certain of said lines when calling and any desired one of certain of said lines, said switch operating only as a finder switch, and a set of keys at the subscriber's station of each of said first mentioned certain lines for controlling the operation of said finder switch, each of said sets of keys including a dif-

ferent key for calling each of said last mentioned certain lines.

6. In a telephone system comprising subscribers' lines, normally-employed switching means for establishing connections between any two of said lines, a switch for establishing direct connections between any one of certain of said lines when calling and a particular one of said lines, said switch operating only as a finder switch, a key at the subscriber's station of each of said certain lines for initiating and controlling the operation of said finder switch to establish connection between the calling one of said certain lines and said particular line.

7. In a telephone system comprising subscribers' lines, normally-employed switching means for establishing connections between any two of said lines, a switch for establishing direct connections between any one of certain of said lines and any of other certain ones of said lines, said switch operating only as a finder switch, and a set of keys at the subscriber's station of each of said certain lines for controlling the operation of said finder switch, each of said sets of keys including a different key for calling each of said other certain lines.

8. In a telephone system comprising subscribers' lines and means for establishing connections between any two of said lines, a switch having one set of brushes for connecting directly with a calling line and another set of brushes for connecting directly with a called line, certain but not all of said lines being connected to terminals with which the brushes of said first set can engage and certain but not all of said lines being connected to the terminals with which the brushes of said other set can engage, said switch operating only as a finder switch.

9. In a telephone system comprising subscribers' lines and means for establishing connections between any two of said lines, a finder switch having one set of brushes for connecting directly with a calling line and another set of brushes for connecting directly with a called line, each of certain but not all of said lines being connected to terminals with which the brushes of said first set engage in succeeding positions of the switch, and each of certain but not all of said lines being connected to a different set of the terminals with which the brushes of said second set engage when the brushes of said first set are in engagement with each of the succeeding sets of terminals to which each of said first mentioned certain lines are connected.

10. In a telephone system comprising subscribers' lines and means for establishing connections between any two of said lines, a switch having one set of brushes for connecting directly with a calling line and a second set of brushes for connecting directly with a called line, each of certain but not all of said lines being connected to terminals with which the brushes of said first set can engage and each of certain but not all of said lines being connected to terminals with which the brushes of said second set can engage, said two sets of brushes being effective in different positions to connect each of said first mentioned certain lines with each of said last mentioned certain lines, said switch operating only as a finder switch.

11. In a telephone system according to claim 10, a set of keys at the subscriber's station of each of said first mentioned certain lines for controlling the operation of said finder switch, each

of said sets of keys including a different key for calling each of said last mentioned certain lines.

12. In a telephone system according to claim 10, a set of non-locking keys at the subscriber's station of each of said first mentioned certain lines for use in initiating and controlling the operation of said finder switch, each of said sets of keys including a different key for calling each of said last mentioned certain lines.

13. In a telephone system according to claim 2, a key at the subscriber's station of each of said certain lines for controlling the operation of said finder switch, and relay means controlled by the receiver hook at a calling station for completing a talking connection through the brushes of said switch between the calling station and said particular station.

14. In a telephone system according to claim 2, a set of non-locking keys at the subscriber's station of each of said certain lines for controlling the operation of said finder switch, means responsive to the temporary operation of the key at the station of one of said certain lines for initiating and controlling the operation of said switch, and relay means controlled by the receiver hook at the calling station for testing the busy or idle condition of said particular line.

15. In a telephone system according to claim 10, a set of non-locking keys at the subscriber's station of each of said first mentioned certain lines for use in initiating and controlling the operation of said finder switch, each of said sets of keys including a different key for calling each of said last mentioned certain lines, a supervisory relay, and means effective upon said switch being advanced to a position in which its brushes are engaged with the terminals of a calling line and the called line for connecting said supervisory relay to said calling line.

16. In a telephone system according to claim 10, a set of non-locking keys at the subscriber's station of each of said first mentioned certain lines for use in initiating and controlling the operation of said finder switch, each of said sets of keys including a different key for calling each of said last mentioned certain lines, and relay means controlled by the receiver hook at a calling line for completing the connection through the brushes of said switch between said calling line and the called line.

17. In a telephone system according to claim 10, a set of non-locking keys at the subscriber's station of each of said first mentioned certain lines for use in initiating and controlling the operation of said finder switch, each of said sets of keys including a different key for calling each of said last mentioned certain lines, a supervisory relay, means effective upon said switch being advanced to a position in which its brushes are engaged with the terminals of a calling line and the called line for connecting said supervisory relay to said calling line, means effective upon operation of said supervisory relay over the calling line for completing a talking connection

through the brushes of said switch between said calling and called lines, and means effective upon release of said supervisory relay when the calling subscriber replaces the receiver for releasing the connection between said lines.

18. In a telephone system according to claim 10, means comprising keys at each station of said first mentioned certain lines for initiating and controlling the operation of said finder switch, a supervisory relay connected to a calling line upon advance of the switch into engagement with the terminals of a calling and a called line and controlled by the receiver hook at the calling line, and means controlled by said relay for testing the called line to determine whether it is busy or idle.

19. In a telephone system according to claim 10, means comprising keys at each station of said first mentioned certain lines for initiating and controlling the operation of said finder switch, a supervisory relay connected to a calling line upon advance of the switch into engagement with the terminals of a calling and a called line and controlled by the receiver hook at the calling line, and means controlled by said relay for testing the called line, for ringing the called station if the called line is idle or as soon after operation of said relay as said called line becomes idle.

20. In a telephone system comprising subscribers' lines and means for establishing connections between any two of said lines, finder switches, each switch having one set of brushes for connecting directly with a calling line and another set of brushes for connecting with a called line, each of certain of said lines being connected to terminals with which the first set of brushes of each of said switches can engage, and each of certain of said lines being connected to terminals with which the other set of brushes of each of said switches can engage, keys at each of said first mentioned stations, a different key for each of said last mentioned certain stations with which direct connection may be desired, and means comprising the key at a calling station which identifies the one of said last mentioned lines with which connection is desired for initiating the operation of the idle ones of said finder switches and for stopping one of said switches in a position in which its brushes are in engagement with the terminals of the calling and called lines, the two brush sets moving together and to the same extent to connect with the calling and called lines.

21. In a telephone system comprising subscribers' lines, switching means for establishing connections between any two of said lines, and other switching means for establishing direct connections between calling and called lines, said other switching means comprising a unidirectional finder switch having two sets of brushes one set for connecting with the calling line and the other set for connecting with a called line, said switch operating solely as a finder switch.

ESMOND PHILIP GOODWIN WRIGHT.
